UNITED STATES PATENT OFFICE.

HERMANN JAWORSKI, OF NEW HAVEN, CONNECTICUT, ASSIGNOR TO
SARGENT & CO., OF SAME PLACE.

DESIGN FOR DOOR-PULL.

SPECIFICATION forming part of Design No. 11,816, dated June 8, 1880.

Application filed May 10, 1880. Term of patent 14 years.

To all whom it may concern:

Be it known that I, HERMANN JAWORSKI, of New Haven, in the county of New Haven and State of Connecticut, have invented a new 5 Design for Door-Pulls; and I do hereby declare the following, when taken in connection with the accompanying drawings and the letters of reference marked thereon, to be a full, clear, and exact description of the same, and 10 which said drawings constitute part of this specification, and represent, in—

Figure 1, front view of the plate; Fig. 2, front view of the handle.

This invention relates to a design for the 15 plate and handle, which are together attached to a door to serve as a convenient means for opening or closing the door, and commonly called "door-pulls;" and the design consists in the configuration and ornamentation of the 20 plate and of the handle, as shown in the accompanying illustrations.

The body of the plate is in form of a parallelogram, each side, near each end, turning outward at an angle of about forty-five degrees, 25 thence contracting and terminating in a half-quarterfoil-shaped tip. This gives the general outline of the plate. Its ornamentation is produced by bands A transversely across its face and apparently projecting slightly from the 30 surface. From the bands, around each end, and between the bands, a border surrounds the edge, forming a panel-surface. Between the bands a series of points are formed on the surface inside the, edge pointing inward. At the 35 center on each edge is an enlargement, segment-shaped, the surface ornamented by a fan-shaped ornament. On the face, at the center, is a diagonal band, B, extending from the points at one side to the points on the opposite side, with a transverse narrower band above and below, connecting with the diagonal band by ribs on the surface. On the tips 40 is a fan-shaped ornament, and at the ends of the body of the plate a series of points turn inward toward the panel. The surface between the parts described is ornamented by floriated tracery, as shown in the accompanying 45 illustration.

The handle between the two arms C C presents the usual outline. The surface is ornamented by a series of points along each edge, turning inward, and at the center is a rosette surrounded by a ring with diagonal ribs running from the central rib and the ring toward each side. The tips of the handle consist of 50 a frustum of a cone-shaped base, D, longitudinally reeded, and on this base the tip proper is placed.

The handle and plate are designed to be used together; but a handle of different design 55 may be used with the plate, or vice versa. The design therefore is not to be understood as limited to the combination of the particular handle and plate shown.

I claim—

1. The design for door-pull plate, consisting of the body in form of a parallelogram, turning angularly outward at each edge, near each end, thence tipped with a half-quarterfoil shape, as shown in the accompanying illustration. 65

2. The design for door-pull plate, consisting of the body in form of a parallelogram, with a transverse band, A, on the surface, near each end, with a border extending from each 70 band around the plate and along the edge between the bands, and a series of points adjacent to said border between the bands, and at each end with a diagonal band, B, at the center between the borders, and transverse band 75 above and below, and connected to said diagonal band by ribs on the surface, as shown in the accompanying illustrations.

3. The design for door-pull handle, consisting of the series of points forming a border 80 for the edge, with a rosette at the center and diagonal ribs on the surface, extending from the central line toward the border, as shown in the accompanying illustrations. 85

HERMANN JAWORSKI.
